UNITED STATES PATENT OFFICE.

GERALD P. AYERS, OF CHICAGO, ILLINOIS.

ICE-REMOVER.

No. 847,453.

Specification of Letters Patent.

Patented March 19, 1907.

Application filed April 30, 1906. Serial No. 314,393.

To all whom it may concern:

Be it known that I, GERALD P. AYERS, a citizen of the United States, and a resident of the city of Chicago, county of Cook, and 5 State of Illinois, have invented certain new and useful Improvements in Ice-Removers; and I do hereby declare that the following is a full, clear, and exact description of the same, reference being had to the accompanying drawings, and to the letters of reference marked thereon, which form a part of this 10 specification.

This invention relates to improvements in ice-removers, and more particularly to an 15 ice-remover adapted to remove ice from third rails of electric railways.

Heretofore considerable difficulty has been 20 encountered by the accumulation of ice upon third rails of electric railways, which oftentimes forms to such an extent as to seriously delay or entirely stop traffic. Various scraping devices attached to the car have been resorted to to remove the ice; but these are 25 generally inefficient when the ice is solid on the rails, in which case it has been necessary for workmen to precede the train and break up or loosen the ice with hammers or the like. This method is not only costly, but is 30 also very slow and causes great inconvenience to travel.

The object of this invention is to provide power-operated means adapted to be attached to the motor-car and to break up the ice and remove it from the rail as the car 35 moves along the track, thereby not only greatly reducing the expense, but greatly economizing in time.

The invention consists in the matters hereinafter described, and more fully pointed out 40 and defined in the appended claims.

In the drawings, Figure 1 is a fragmentary side elevation of a car provided with an ice-remover embodying my invention. Fig. 2 is a transverse section of the same. Fig. 3 is 45 an enlarged side elevation of the car-trucks and attached ice-remover. Fig. 4 is an enlarged fragmentary side elevation of the remover. Fig. 5 is a bottom plan or face view of the hammer, and Fig. 6 is an end elevation 50 of the hammer at the lower limit of its movement and showing the rail in section.

As shown in said drawings, A represents a car of any preferred construction, and A' represents one of the trucks thereof, the 55 equalizing-bars a of which are each provided with an insulator-bar a' , on which at the rear

end thereof is a contact-shoe A^2 , of any preferred construction, through which the current is transmitted to the motor A^3 . At the forward ends of said equalizing-bars a and a' separated therefrom by said insulator-bars are the ice-removers B , each of which, as shown, comprise a pneumatic cylinder of any preferred construction which is rigidly engaged to said equalizing-bar and insulator a by means of apertured lugs b integral with said cylinder and through which said cylinder is rigidly bolted to the bar. A supply-pipe b^2 leads from a main pressure-pipe B' , connected with the main pressure-cylinder of the brake system (not shown) through the motorman's cab and downwardly to near each cylinder b , to which it is connected by means of a rubber hose or the like b^5 , thereby insulating the pipes from the cylinder. Said pipes b^2 are provided in the motorman's cab with controlling-valves b^3 , by means of which the passage of air to said cylinders is controlled. The piston-rod b^4 projects from the lower end of said cylinder directly above the third rail, and rigidly engaged thereon is the head or hammer C , which, as shown, comprises a rigid block of metal of a width approximately equal to the width of the rail-head and of any preferred length. The face 85 of said hammer, as shown more clearly in Figs. 4 and 6, is curved upwardly at its end and is provided throughout the length thereof with a plurality of sharp ridges or edges c , which, as shown, extend diagonally across 90 said face to enable the same to more readily break the ice from the top of the rail, though obviously any other desired configuration for the face of said hammer may be provided.

Intermediate the contact-shoe A^2 and the ice-remover B is the scraper or brush D , of any desired or usual construction, adapted to remove any particles of ice which may be left upon the rail after the passage of the hammer C , thereby leaving the rail clean for 100 the passage of the contact-shoe.

The operation is as follows: Inasmuch as the ice-remover is detachably engaged upon the car, it is obvious that when not required it may be removed and stored away or carried within the car, as preferred. When, however, it is desired to utilize the same, it is attached to the equalizer-bar of the truck, as shown in Figs. 1 and 3, and is connected with the air-supply or other power used in 110 operating the same. By means of the valve b^3 in the supply-pipe the hammer may be set

in motion, and the throw thereof is such that when at its lower limit it just contacts the top of the rail E, thereby cutting through the ice for its entire thickness. Owing to the 5 rapid reciprocation of the hammer, the ice is thoroughly chopped or broken from the top of the rail, and such particles thereof as are not thrown off by the action of the hammer are removed by the passage of the scraper or 10 brush D, thereby leaving the rail thoroughly cleaned.

While I have shown my device operated by 15 pneumatic power, it is obvious that, if preferred, it may be operated by electric or 20 any motive power used to drive the car, and obviously the car may be provided at each end with the remover B to enable the 25 car to be run in either direction without turning around.

20 I claim as my invention—

1. In an ice-remover the combination with 25 a car-truck of a power-operated hammer carried thereon directly above the third rail and means for operating said hammer to force it 30 downwardly into close contact with the top of the rail.

2. In an ice-remover the combination with 35 a car-truck of a hammer supported thereon above the third rail and having its ends 40 rounded on the under face and means for reciprocating said hammer.

3. In an ice-remover for third rails, the 45 combination with a car-truck of a vertically-reciprocating hammer carried thereon and

adapted to break ice from the rail said hammer having an elongated roughened face curved upwardly at the ends. 50

4. In a device of the class described the 55 combination with a car of a vertically-reciprocating hammer carried on the truck 40 thereof an elongated head on said hammer extending longitudinally of the third rail and having its ends rounded on the under face and means for operating said hammer.

5. In a device of the class described the 45 combination with a car of a pneumatic cylinder carried thereon, a reciprocating piston in said cylinder, an elongated hammer on the end thereof provided with a roughened face and upwardly-curved ends and a pressure-pipe adapted to supply power to said cylinder. 50

6. In a device of the class described the combination with a car and the trucks thereof, of a pneumatic cylinder engaged on 55 the side of the trucks above the third rail, a reciprocating piston in said cylinder, an elongated hammer thereon extending longitudinally of the rail, means for supplying air to said cylinder and a valve controlling the 60 air-supply.

In testimony whereof I have hereunto subscribed my name in the presence of two subscribing witnesses.

GERALD P. AYERS.
